UNITED STATES PATENT OFFICE

2,415,682

WINDOW SCREEN HANGER

Edward Fixter, St. Petersburg, Fla.

Application May 11, 1945, Serial No. 593,281

4 Claims. (Cl. 160—362)

1

The present invention relates to new and useful improvements in hanger for window screens and has for its primary object to provide means for easily and quickly hanging the screen on a window frame from the inside of the window.

An important object of the present invention is to provide spring means connecting the sides of the window screen to the blind stop of the window casing and by means of which the spring exerts its influence on the screen in an upward and inward direction to yieldably maintain the screen in its desired position in the window frame without requiring the use of screws or other fastening devices.

A further object of the invention is to provide a prop adapted for connecting the screen to the window frame and for swinging the screen outwardly into a position to facilitate washing of the windows, when desired.

A still further object of the invention is to provide a device of this character of simple and practical construction, which is neat and attractive in appearance, efficient and reliable in use, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout and in which:

Figure 1 is a view in elevation of the inside of the screen.

Figure 2 is a vertical sectional view taken substantially on a line 2—2 of Figure 1 and showing the screen in closed position.

Figure 3 is a similar view showing the screen in open position.

Figure 4 is a sectional view taken substantially on a line 4—4 of Figure 3.

Figure 5 is a bottom plan view of the wear plate for the retaining pins on the upper edge of the screen, and

Figure 6 is a fragmentary vertical sectional view of the wear plate and pin inserted therein.

Referring now to the drawings in detail, wherein for the purpose of illustration I have disclosed a preferred embodiment of the invention, the numeral 5 designates the outside window casing positioned over the blind stop 6 and which forms one of the guides for a sliding sash (not shown) mounted in the casing.

The lower edge of the casing 5 is formed with a pair of upwardly extending recesses 7 over which wear plates 8 are secured by means of nails,

2

screws, or the like 9, the wear plates having an opening 10 registering with the recesses 7.

The window screen is designated generally at 11 and includes the top rail 12 and side rails 13.

5 A pin 14 is threaded or otherwise driven into the top rail 12 to project upwardly therefrom for insertion through each of the openings 10 into one of the recesses 7.

The opening 10 and recess 7 are of a diameter substantially in excess of the diameter of the pin 14 to provide for the free movement of the pin in the opening and recess and to permit the outward swinging movement of the screen from the position as shown in Figure 2 of the drawings to the position as shown in Figure 3, without bending or distorting the pin.

The screen 11 is held in an upright position against the blind stop 6 by means of a pair of coil springs 15 having their upper ends attached 15 to the blind stop 6 by means of screw eyes 16 and having their lower ends attached to the side rails 13 of the screen by means of screw eyes 17.

As will be apparent from an inspection of Figure 2 of the drawings, the lower end of the spring 20 extends in an outwardly inclined direction so that the spring exerts its influence upwardly and inwardly upon the screen to draw the screen upwardly against the casing 5 and inwardly against the blind stop 6.

30 When it is desired to support the screen 11 in an outwardly inclined position, as shown in Figure 3 of the drawings for the purpose of cleaning the window sash, a prop 18 of the strap iron is provided at one end with an opening 19 loosely pivoted on a screw or the like 20 secured to the side of the blind stop 6 and the other end of the prop 18 is bent angularly, as indicated at 21, for bearing against the inner side of the side rail 13 of the screen and terminates in an outwardly projecting end 22 having an opening 23 therein for loosely receiving a screw 24 secured to the inner side edge of the side rail 13 of the screen.

By reason of the enlarged openings 19 and 23 in the ends of the prop 18, the same may be 45 easily and quickly mounted on their respective screws 20 and 24 without necessitating frequent removal of the screws and the prop accordingly may be removed from the window frame and stored in an out-of-the-way position when not in use.

When the window screen is swung outwardly and supported by the prop 18, the spring 15 will urge the upper end of the screen against the casing 5 and thus maintain the screen in the proper position in the window frame so that

the screen may swing downwardly against the blind stop when the prop is removed.

As is apparent in Figure 1, the springs 15 have their lower eyes closed so as to be permanently linked with the eye screw 11, while the upper eyes are open and act as hooks, cooperative with the eye screws 16 in the blind stop 6.

The purpose in having the springs 15 thus connected is so that the springs can be easily stretched upwardly to hook over the eye screw 16 and when, for any purpose the springs are to be disconnected, the springs can be unhooked from the eye screws 16 and held as handles in removing or positioning the screen in place.

While the foregoing description sets forth the invention in specific terms, it is to be understood that numerous changes in the size, shape and materials may be resorted to without departing from the spirit of the invention as claimed hereinafter.

Having thus described the invention what I claim is:

1. A window screen hanger comprising a pin projecting upwardly from the top rail of a screen, a window casing having a recess in the upper part thereof, said pin being adapted for insertion in said recess, and spring means connecting the screen to the casing.

2. A window screen hanger comprising a pin projecting upwardly from the top rail of a screen, a window casing having a recess in the upper part thereof, said pin being adapted for insertion in said recess, and spring means connecting the screen to the casing and exerting its in-

fluence upwardly and inwardly on the screen to urge the screen upwardly and inwardly against the casing.

3. A window screen hanger comprising a pin projecting upwardly from the top rail of a screen, a window casing having a recess in the upper part thereof, said pin being adapted for insertion in said recess, and a pair of coil springs connecting the sides of the screen to the top of the casing and exerting an upwardly and inwardly pulling force on the screen.

4. A window screen hanger comprising a pin projecting upwardly from the top rail of a screen, a window casing having a recess in the upper part thereof, said pin being adapted for insertion in said recess, a pair of coil springs connecting the sides of the screen to the top of the casing and exerting an upwardly and inwardly pulling force on the screen to maintain the pin in said recess, and a wear plate covering the recess and having an opening receiving the pin.

EDWARD FIXTER.
